UNITED STATES PATENT OFFICE.

FRANK H. HOBERG, OF GREEN BAY, WISCONSIN.

PAPER-CABINET.

1,183,976.

Specification of Letters Patent. Patented May 23, 1916.

Application filed January 15, 1914. Serial No. 812,215.

To all whom it may concern:

Be it known that I, FRANK H. HOBERG, a citizen of the United States residing at Green Bay, county of Brown, and State of Wisconsin, have invented new and useful Improvements in Paper-Cabinets, of which the following is a specification.

My invention relates to improvements in paper cabinets of that class which are designed to receive paper packages wound in the form of an oval strip, said strip being divided into sheets by perforate or weakened lines coinciding at the top of the package, whereby one end of the outer sheet will drop and be exposed through the bottom of a cabinet in a position to be grasped and torn off.

The present invention relates more particularly to cabinets designed to receive paper toweling wound in the form of an oval package of the above described type, and the object of my invention is to provide means for insuring the release and discharge of the loose end of each successive sheet after the preceding sheet has been torn away, said means being also adapted to prevent the release and discharge of the loose end of the sheet until the user has operated an actuating member connected therewith. The delivery of the successive sheets is therefore not only reliable, but it is delayed by requiring an intervening operation of an actuating member or knob, whereby waste and fraud in the withdrawal of an unnecessary number of sheets are prevented.

A further object of my invention is to provide an improved form of cabinet or container for such packages in which it will not be possible for the package to be bodily withdrawn after it has been inserted in position for use.

In the drawings,—Figure 1 is a sectional view of a towel cabinet with a package of toweling therein, drawn on line $x-x$ of Fig. 2. Fig. 2 is a sectional view of the same drawn on line $y-y$ of Fig. 1. Fig. 3 is a plan view of a package of toweling, showing the partially severed line or lines of weakness.

Like parts are identified by the same reference characters throughout the several views.

The lower end of my improved cabinet is open. The cabinet comprises a back wall A , end walls B , B' , and hinged cap plate which forms the front wall C and the top

wall D , said plate being hinged to the side walls B , B' , at b , near their lower front corners. The package E of paper toweling is wound upon an oval paste board core E' and is supported from the end walls of the cabinet by a hanger plate F . This hanger plate or bar F comprises a narrow flat bar of metal, which extends through slots f , f' , in the paste board core, substantially opposite the median line. At one end the plate F is provided with an outwardly projecting arm F' , which extends into an open ended slot or slit e formed in the core E' and package E , thereby preventing the package from rotating upon the core.

One end of the bar F is provided with a beveled portion g , whereby when it is pushed upwardly in the lower end of the cabinet, it will readily pass into registry with and be received in a retaining pocket g' formed in the end wall B' of the cabinet. At the other end of the bar F , a movable member G is mounted upon the bar to slide between guides H . The outer margin of this movable member is beveled at G' , the shape of this member being similar to the other end of the bar F at g . The movable member G , however, is provided with a rearwardly extending portion h seated against a spring h' , which is mounted in a pocket h'' formed on the side of the bar F . The member H is also slotted at I and is loosely held to the bar F by a rivet I' which permits a slight forward and backward movement of said member G .

The object of the movable member G is to make the bar F resiliently extensible so that when said bar F , with a package thereon, is pushed upwardly in the cabinet from beneath, the member G and bar F will move inwardly or telescope upon each other sufficiently to permit the end margins to pass the walls of the retaining pocket g' and i .

As soon as the end g of the bar F has entered the pocket g' and the movable member G is brought in registry with the pocket i , said member G moves resiliently into said pocket i and locks the bar and the package in the cabinet. The free end of the outer sheet of the package being swung downwardly and the tearing line of the package being at the top, it is obvious that as each sheet is torn off, the free end of the second sheet will tend to drop and be exposed through the open lower end of the cabinet.

In the use of packages of the described

class, it has been found that the sheets tend to adhere at times so that the free end of the outer sheet will not always drop. This is particularly true of toweling where crepe paper is usually employed, and it is therefore desirable to provide means for initially actuating the sheet, and it is also desirable to prevent the free end of the sheet from dropping until it is so initially actuated, 10 since otherwise the successive sheets could be torn off rapidly and would be wasted.

For initially actuating the free ends of the sheets, I employ a friction roller J, said roller being suspended by a swinging 15 frame or hanger J', which is pivoted to the casing at j, j', respectively. The roller J is mounted upon a shaft K, which is journaled in this swinging frame. The frame is pivoted to the casing, preferably on an 20 axis cutting the vertical center line of the package, and as the sheets are withdrawn from the package, the roller J is free to move downwardly by gravity, so that its surface bears continuously with uniform 25 pressure upon the surface of the package. The outer surface of the roller is formed of a material which is adapted to move with sufficient friction upon the paper to actuate the outer sheet. The roller J is actuated 30 from the exterior by means of a knob L, which transmits motion to the roller J through a shaft L', gear wheel M and a pinion N, the latter being fast upon a projecting end of the roller shaft K. The shaft 35 L', upon which the knob and gear wheel M are mounted, projects through a fixed bearing member O in the casing, the gear wheel being located in the interior of the casing.

In operation, the package of toweling being 40 inserted in position within the cabinet from below, the knob L may be turned in the direction indicated by the arrow, whereupon the end of the strip of toweling will be thrown downwardly and permitted to 45 hang, as shown at P in Fig. 1. The user grasps this hanging sheet and pulls it off, the sheet separating from the package at the top where it is slitted, as indicated at p, p' in Fig. 3, said sheet being connected 50 with the remainder of the package only along the dotted lines Q (Fig. 3), and therefore tearing radially at these points. When the initial sheet has been thus torn off, it is necessary to again rotate the knob L in 55 the direction indicated by the arrow in order to move the free end of the succeeding sheet downwardly and permit it to hang, as indicated at P in Fig. 1. Two operations are therefore required for the removal of 60 each sheet in that it is necessary to first turn the knob and then pull upon the sheet which the roller J moves downwardly.

The cap plate C D is preferably provided 65 with a spring latch R adapted to engage a catch S, and I preferably also provide a

small push button T, whereby the latch may be released if desired, but the specific mechanism for securing the cap plate or cover is not essential to this invention.

I claim—

1. The combination with an inclosing cabinet having its lower end wholly open and provided with a holder for oval packages of rolled paper, and means for preventing said rolled packages from rotating upon said holder, of a swinging support mounted in the upper portion of said cabinet, a roller journaled in said support in a position to swing against a package of paper in said cabinet, and means for actuating said roller from the exterior. 70

2. The combination with an inclosing cabinet provided with a holder for oval packages, of a swinging support mounted in the upper portion of said cabinet, a roller journaled in said support in a position to swing against a package of paper in said cabinet, and means for actuating said roller from the exterior, said means comprising a shaft extending through one wall of said cabinet, an exterior knob mounted on said shaft, an interior gear wheel mounted on said shaft, and a pinion connected with the roller and meshing with said gear wheel. 75

3. The combination with a paper holding cabinet designed to receive oval packages of rolled paper, of a friction roller movably mounted in said cabinet and adapted to bear against one side of the upper portion of such package, and means for rotating said roller from the exterior, said roller being adapted to move against the remaining sheets as successive sheets are withdrawn, and a holder provided with an arm adapted to project through a slit in the roll of paper to prevent it from turning, whereby each sheet detached from the roll is permitted to drop and hang through the lower end of the cabinet. 80

4. The combination with a cabinet for oval paper packages having end walls provided with interior ledges constituting pockets, of a package holder comprising a flat extensible bar adapted to pass through slits in a paper package core, said bar having a flat resiliently extensible member at one end, whereby it is permitted to contract longitudinally while moving across said ledges into registry with the pockets, said bar being resiliently extensible into said pockets. 85

5. The combination with a cabinet for oval paper packages having end walls provided with interior ledges forming pockets, of a package holder comprising a flat extensible bar adapted for interlocking engagement with a package of paper and having a resiliently extensible member composed of similar material in side contact with the flat bar and having upper and lower edges substantially in the same vertical plane, 90

said expandible member being adapted to permit said bar to contract in length while moving across said ledges into registry with the pockets and to automatically expand in length when in registry with said pockets, together with a hollow core upon which said package is wound, provided with a plurality of slits through which said bar is interlaced to prevent rotation of the core and package about said bar, substantially as described.

5 6. The combination with an inclosing cabinet provided with a holder of packages of wound strips of paper, separable at the top of the package into sheets, of a sheet retainer adapted to bear against the upper portion of the package adjacent to the sepa-

rating point, a roll retainer connected with the holder and adapted to prevent rotation of the wound package upon the holder, and 20 means for actuating said retainer from the exterior to start a sheet and discharge one end thereof from the cabinet, said cabinet being open at the bottom to a sufficient extent to allow sheets of paper to drop by 25 gravity from the roll and hang in a suspended position through the lower end of the cabinet.

In testimony whereof I affix my signature in the presence of two witnesses,

FRANK H. HOBERG.
